STARTING APPARATUS FOR INTERNAL COMBUSTION ENGINES

Filed May 12, 1932

UNITED STATES PATENT OFFICE

1,935,372

STARTING APPARATUS FOR INTERNAL COMBUSTION ENGINES

Mortimer S. Parkhill, Corning, N. Y., assignor to Ingersoll-Rand Company, Jersey City, N. J., a corporation of New Jersey

Application May 12, 1932. Serial No. 610,859

4 Claims. (Cl. 60—16)

This invention relates to internal combustion engines and more particularly to starting apparatus therefor.

The invention has for its object to facilitate the starting of internal combustion engines of large size.

A further object of the invention is to enable compression in the engine cylinder to be relieved while the fly-wheel is being rotated to a suitable starting position.

Other objects and advantages thereof will be in part obvious and in part pointed out hereinafter.

The invention will be more completely understood by reference to the accompanying drawing, in which,

Fig. 1 is a longitudinal section through the cylinder of an internal combustion engine embodying the invention, and

Fig. 2 is a transverse section through the distributor.

Referring to the drawing and more particularly to Fig. 1 the engine comprises a cylinder 10 and a piston 12 adapted to reciprocate therein. The piston is attached in a suitable manner by means of a piston rod 14 to a cross-head 16 adapted to slide in a cross-head guide 18. A cross-head pin 20 journaled on the end of the connecting rod 22 connects the cross-head 16 to the crank pin 24 of the crank shaft 26 upon which is mounted a fly-wheel 28. The cylinder 10 is provided with a suitable head 30.

While the invention is equally suitable for use in any form of reciprocating internal combustion engine, the particular form here shown is adapted to consume gas and for this purpose a suitable mixing throttle valve 32 is provided connected by means of the manifold 34 to the valve inlet chamber 36 controlled by an inlet valve 38. A valve 40 is also provided for the discharge of the burned gases.

The inlet and exhaust valves 38 and 40 are operated by rocker arms 42 only one of which is shown, driven by suitable cams 44 on the cam shaft 46. Preferably the cam shaft 46 is driven in this instance at half the crank shaft speed by a train of gears 48 and 50 actuated by a sprocket 52 connected by a chain 54 to a sprocket 56 on the crank shaft 26.

The engine may include as many cylinders as desired in this instance, there being two, the cylinder 11 being substantially identical with the cylinder 10.

Large engines of the character above described are usually started by air pressure admitted to

the cylinder 10 as a substitute for the explosive mixture, the air being distributed to the cylinders by suitable timing apparatus. Such an arrangement is provided in this instance, there being a distributor valve 58 supplied with air from a receptacle 60 and its compressor 61 by means of a pipe 62 provided with an air starting valve 64 and distributing the supply of air by means of pipes 66 and 68 to the cylinders 10 and 11 respectively. The distributor 58 comprises a body 70 having an air inlet chamber 72 into which the pipe 62 leads, and two discharge chambers 74 and 76 to which the pipes 66 and 68 respectively are connected.

Communication between the chamber 72 and the chambers 74 and 76 is controlled by tappet valves 78 and 80 respectively which are actuated by rocker arms 82 and 84 respectively. The arms 82 and 84 are rocked upon their pivot 86 by a cam 88 mounted on the cam shaft 46.

Each of the pipes 66 and 68 lead to a valve casting 90 which is inserted into the head 30 of the cylinder 10 or 11 through an aperture 92 and seats tightly on the inner wall 94 of the head.

The valve casting 90 is hollow, being provided with a passageway 96 with which pipes 66 and 68 communicate, this passage terminating at the valve seat 97 which opens into the interior of the cylinder. A check valve 98 seating on the seat 97 is provided with a stem 100 which extends through a close-fitting bore 102 in the valve casting 90 and terminates in a threaded portion 104 upon which is mounted a hand-wheel 106. The hand-wheel 106 is prevented from being unscrewed on the end of the valve stem 100 by means of an abutment 108 mounted on the threaded end 104.

The check valve 98 is normally held seated by means of a spring 110 about the threaded end 104 of the valve and pressing against the hand-wheel 106 at one end and at the other end seating at the bottom of a recess 112 in the valve casting 90. The hand-wheel 106 is adapted to be screwed up upon the threaded end 104 of the valve to hold the valve 98 rigidly upon its seat in which position the spring 110 is compressed within the recess 112 and the hand-wheel 106 abuts the outer face of the casting 90. When the hand-wheel is in its outermost position against the abutment 108 the valve may be held partly off its seat by means of a latch 114 pivotally attached to a lug 116 on the casting 90 and having a hook end 118 for the engagement with the rim of the hand-wheel 106.

In starting an engine of the type above de-

110

scribed the procedure is to rotate the fly-wheel 28 to a position at which the piston 12 is at the beginning of its stroke away from the head 30. When in this position the valve 64 may be opened 5 to admit air to the distributor 58 and thence to the cylinder. However, it is very difficult to so rotate the fly-wheel unless provision is made for permitting the air displaced by movement of the piston to escape from the cylinder. By this invention the check valve 98 is utilized as a means 10 of escape for this air and to this end the latch 114 is adapted to engage the hand-wheel 106 to depress the valve 98 against the pressure of the spring 110. Therefore, in preparation to turning 15 the fly-wheel the hand-wheel 106 is screwed out against the abutment 108 and pushed in against the pressure of the spring 110 and the latch 114 is then slipped over the hand-wheel. Preferably the valve 98 is held by the latch 114 just slightly 20 off its seat 97. While the valve is in this position the air pumped out through the seat 96 passes back through the pipe 66 into the chamber 74 through the chamber 72 and thence into the chamber 76 and pipe 68 to the valve casing 25 90 of the cylinder 11.

The valve 98 of the cylinder 11 is similarly held off its seat by its latch 114, therefore the atmospheric air ejected from the cylinder 10 passes into the cylinder 11 and thence to atmosphere 30 past the valves 38 or 40 of the cylinder 11.

It is to be understood that the valves 78 and 35 80 of the distributor 58 drop off their seats by gravity, while the pressure in the chambers 72, 74 and 76 is equalized.

The piston 12 having been brought to a position 40 which it occupies at the beginning of its power stroke when operating as a combustion engine, the valves 64 may be opened to admit air under pressure to the chamber 72 whereupon the air pressure closes the valve 80 and passes 45 through the pipe 66 to the passageway 96 of the valve casing 90 and thence past the valve 98 into the cylinder 10. The pressure of the air, however, is sufficient to throw the valve 98 further open whereupon the latch 114 is released from the hand-wheel 106 permitting the latch 114 to drop by gravity. Upon being released the valve 98 operates in its normal manner as a check valve 50 and prevents return of compressed gas from the cylinder 10.

Thus by the above described construction are

accomplished, amongst others, the objects and advantages hereinbefore referred to.

I claim:

1. Starting apparatus for reciprocating internal combustion engines comprising a source of compressed air, timed distributor means for controlling the flow of air from said source to the cylinder of said engine, a conduit leading from said distributor to the cylinder, a check valve associated with said conduit and being actuated by the compressed air flowing into the cylinder of the engine, and means for holding said check valve open and being automatically released upon movement of the check valve. 80

85

2. Starting apparatus for reciprocating internal combustion engines comprising a source of compressed air, timed distributor means for controlling the flow of air from said source to the cylinder of said engine, a conduit leading from said distributor to the cylinder, a check valve associated with said conduit and having a stem, said check valve being actuated by the compressed air flowing into the cylinder of the engine and means for holding said check valve open, comprising a latch to engage said stem and being automatically released from the check valve upon movement of the check valve. 90

95

3. Starting apparatus for reciprocating internal combustion engines comprising a source of compressed air, timed distributor means for controlling the flow of air from said source to the cylinder of said engine, a conduit leading from said distributor to the cylinder, a check valve associated with said conduit and automatically releasable means for holding said check valve open, said valve including a threaded stem, a hand-wheel on said stem, a latch engaging said hand-wheel. 100

105

4. Starting apparatus for reciprocating internal combustion engines comprising a source of compressed air, timed distributor means for controlling the flow of air from said source to the cylinder of said engine, a conduit leading from said distributor to the cylinder, and a check valve associated with said conduit, said valve including a hollow casing, a valve extending through said casing and having a threaded end, a hand-wheel, spring means interposed between said casing and said hand-wheel and an automatically releasing latch on said casing to engage said hand-wheel. 115
